ATTYS

UNITED STATES PATENT OFFICE.

ZERA KNAPP, OF NEWCASTLE, INDIANA.

DESIGN FOR A KITCHEN-CABINET TABLE.

41,689.

Specification for Design.

Patented Aug. 15, 1911.

Application filed July 9, 1909. Serial No. 506,857. Term of patent 14 years.

To all whom it may concern:

Be it known that I, ZERA KNAPP, a citizen of the United States, residing at Newcastle, in the county of Henry and State of Indiana, have invented a new, original, and ornamental Design for a Kitchen-Cabinet Table, reference being had to the accompanying drawings.

The figure is a perspective view of the table showing my new design.

What I claim is:

The ornamental design for a kitchen cabinet table as shown.

ZERA KNAPP.
